UNITED STATES PATENT OFFICE.

ANDREW GRAM, OF MENOMINEE, MICHIGAN.

STEAM-ENGINE.

SPECIFICATION forming part of Letters Patent No. 352,537, dated November 16, 1886.

Application filed March 29, 1886. Serial No. 197,034. (No model.)

To all whom it may concern:

Be it known that I, ANDREW GRAM, a citizen of the United States, residing at Menominee, in the county of Menominee and State of Michigan, have invented a new and useful Improvement in Steam-Engines, of which the following is a specification, reference being had to the accompanying drawings.

My invention relates to an improvement in devices for lifting or disconnecting the eccentric hooks of steam-engines from the rocker-arms when it becomes necessary to stop the engine; and it consists in the peculiar construction and combination of devices, that will be more fully set forth hereinafter, and particularly pointed out in the claim.

When it becomes necessary to stop the motion of a single-cylinder stationary steam-engine, it is usual, in order to prevent the said engine from stopping on the dead-center, for the attendant to disconnect the valve from its actuating mechanism by lifting the eccentric hook from its pin in the rocker-arm, when the said valve may be operated by hand, thus enabling the attendant to govern the motion of the engine, so as to cause it to stop at any desired point. This object I accomplish by the devices illustrated in the accompanying drawings, in which—

Figure 1 is a side elevation of the valve mechanism of a steam-engine provided with my improved lifting devices. Fig. 2 is a vertical sectional view of my improvement. Fig. 3 is a detailed elevation of the anti-friction roller.

A is the main engine-shaft, to which is secured the usual eccentric, B.

C represents the eccentric-rod, which has one end connected to the eccentric by means of the usual eccentric-strap, and is provided at its opposite end with a hook, D, which engages a pin, k, that projects from one side of the rocker-arm E. The upper end of the rocker-arm is connected to one end of a pitman, a, the opposite end of which is adapted to be attached to the valve-stem, which latter is not here shown, as it may be of any usual construction, and forms no part of this invention. When the shaft A rotates, vibratory motion is imparted to the valve through the eccentric-rod C, the rocker-arm E, and the pitman a, as will be readily understood.

F represents a vertical steam-cylinder, in which is fitted the piston b. The said piston has a rod, c, which extends through the upper end or head of the cylinder, and to the upper end of the said rod is attached a cross-head, d, in which is journaled a grooved anti-friction roller, e, which bears against the under side of the eccentric-rod, near the free end of the latter. The cylinder is supported on a bracket or shelf, G, which is bolted or fastened to one side of the engine-bed, which latter is not here shown.

H represents a three-way valve, which communicates with steam-pipes l, f, and f', the latter of which extends from the valve to the lower end of the steam-cylinder. An arm, i, is secured to the valve, and the said arm is connected to the hand-lever g by means of a rod, h.

The operation of my invention is as follows: The attendant, by moving the lever g, moves the valve H to the position shown in Fig. 2, thus admitting steam through the pipes f and f' into the lower end of the cylinder F, where it acts against the piston and raises the latter, causing the eccentric-rod to be unshipped from the pin k of the rocker-arm E and raised to the position shown in dotted lines in Fig. 1. This disconnects the rocking arm and the valve-gear from the eccentric-rod, causing the valve to remain stationary and under the control of the attendant.

I do not claim, broadly, the idea of disconnecting the eccentric rods of steam-engines from the rocker-arm. The patent of Wilbraham, No. 137,273, employs a vertically-movable rod operated by a foot-lever to effect this end. There is nothing new, broadly, in the use of a three-way valve with the steam-connections for the cylinder in other classes of invention. Moreover, the use of steam as an agency to effect the disconnection of the eccentric-rod from the rocker-valve is old, as shown in patents of Onslow and Oelert, No. 314,466; hence I wish it understood that my claim is limited to the particular combination of elements as expressed.

Having described my invention, I claim—

In combination with the eccentric-rod C, the steam-cylinder F, the piston b, piston-rod c, the upper end of which rests under the eccentric-rod C, the rocker-arm E, connecting

with the valve-gear of the engine and having a pin, *k*, a notch formed in the rod *C* to receive the pin, the end of the rod beyond the pin providing a handle, the steam-cylinder and its piston being located on the other side of the pin, pipes for admitting steam to and exhausting it from the cylinder, a valve for controlling the passage of steam, and lever-connection for operating the valve, as set forth.

In testimony that I claim the foregoing as my own I have hereto affixed my signature in presence of two witnesses.

ANDREW GRAM.
